ALBERT B. DICK, OF LAKE FOREST, ILLINOIS, ASSIGNOR TO A. B. DICK COMPANY, OF CHICAGO, ILLINOIS, A CORPORATION OF ILLINOIS.

PRINTING-MACHINE.

No. 922,861.

Specification of Letters Patent.

Patented May 25, 1909.

Application filed October 17, 1907. Serial No. 397,771

To all whom it may concern:

Be it known that I, ALBERT B. DICK, a citizen of the United States, residing at Lake Forest, in the county of Lake and State of Illinois, have invented a certain new and useful Improvement in Printing-Machines, of which the following is a specification.

This invention relates to printing-machines and has reference, more particularly, to machines of comparatively small size for use in offices in producing multiple copies of letters and circulars.

The object of the invention is to provide a printing-machine for this use which can be readily and efficiently operated at comparatively high speed by an unskilled operator, by which letters and circulars may be printed in imitation of type-written work, which is so constructed that the type can be readily assembled; and which can be manufactured at low cost.

An embodiment of the invention is illustrated in the accompanying drawings, in which—

Figure 1 is a plan view of the machine broken away and sectioned in part, with some of the parts removed for the sake of clearness; Fig. 2 is a central section on line 2—2 of Fig. 1; Fig. 3 is a detail view of a portion of the type-carrying cylinder; Fig. 4 is a sectional detail view hereinafter referred to; Fig. 5 is a detail view of the platen-roller and the support therefor; Fig. 6 is a detail view of a portion of the type-carrying cylinder; Figs. 7 and 8 are perspective and plan views, respectively, of one of the type-carriers; Fig. 9 is a section on line 9—9 of Fig. 8; and Fig. 10 is a section on line 10—10 of Fig. 8.

Referring to these drawings, the machine consists of a base A on which are mounted side-frames B, B', these frames carrying the type-carrying cylinder C and the platen-roller D. The type-cylinder C consists of a shaft c having heads c', c² (Figs. 1 and 4) secured to the ends thereof but removable therefrom, the head c' being held in position by a nut c³ threaded on one end of shaft c. The frame B is provided with an opening to receive a pin b having a knurled head b' and a reduced end b² adapted to enter an opening in the end of the shaft c. A screw b³ threaded into an opening in the frame B is adapted to engage the pin b to hold it in position. The other end of the type-carrying cylinder C is similarly supported upon a pin e ex-

teuding through an opening in the frame B', its end entering an opening in the end of shaft c.

Keyed on pin e is a gear e' lying adjacent to the end of shaft c, and the key e for this gear enters within a key-way formed in the wall of the opening in the end of shaft c, so that shaft c and the type-carrying cylinder turn with gear e'. This gear meshes with a pinion e² (Fig. 1) carried by a shaft which is journaled in a bearing formed in the side-frame B' and which carries at its outer end a crank provided with a suitable operating handle E. By this construction, it will be seen that when the type-carrying cylinder is mounted in position it is connected to the operating handle E so that it may be rotated thereby and that the cylinder may be readily withdrawn from its position by loosening the screw b³ and withdrawing the pin b, in order that the cylinder may be moved in the direction of its axis a distance sufficient to free the end of shaft c from the end of pin e.

The platen-roller D is mounted directly below the type-carrying cylinder C and is so arranged for adjustment toward and away from the cylinder. For this purpose, the roller D is carried by a shaft d, the ends of which are received in slots formed in the ends of arms d' which are pivoted upon the side-frames B, B'. The ends of arms d' are provided with integral offsets d² (Fig. 5), through which extend screws d³ which may be held in any adjusted position by lock-nuts d⁴. The ends of these screws bear on cams d⁵ carried by a shaft d⁶ which is rotatable in bearings formed in the side-frames, one end of this shaft being extended through the side-frame B' and carrying upon its end a crank d⁷. At its free end this crank is provided with an operating handle d⁸ and a pin d⁹, and the end of this pin is adapted to enter any one of a plurality of depressions d¹⁰ in the side-frame B' arranged in an arc about the axis of shaft d⁶ as a center. When the shaft d⁶ is turned by means of its handle, the cams d⁵ are rotated and coast with the screws d³ to adjust the position of the platen-roller D relatively to the type-carrying cylinder. The shaft d⁶ is held in any adjusted position by the concave condition of the end pin d⁹ with one of the depressions d¹⁰. For an adjustment greater than that which can be obtained by rotating the shaft d⁶ and for obtaining exact parallelism of the platen-roller and type-carrying

cylinder, the screws d^3 may be positioned as may be required in the openings in the offsets d^2 , these screws being then locked in position by the nuts d^4 .

5 A feed-board F is supported upon the side-frames B, B', opposite the line of coaction of the type-carrying cylinder and the platen-roller. Preferably, a sheet-feeding device is provided between this line and the feed-board. This may consist of a pair of rollers f, f' mounted one above the other with their peripheries in contact and connected for simultaneous operation, as shown in Fig. 2. At one side of the machine, a friction-roller 10 f^2 may be provided, geared to the roller f and mounted in position to be engaged intermittently by a sector secured to the type-carrying drum. This sheet-feeding device forms no part of my present invention and I, 15 therefore, consider it unnecessary to describe it in detail.

The type are radially disposed upon the cylinder C, in lines extending circumferentially of the cylinder. A transfer fabric of a 20 width sufficient to cover all of the lines of type extends over the type and has its ends suitably mounted upon the cylinder. This transfer fabric may be a ribbon impregnated with ink, or it may be an unimpregnated fabric arranged to make contact during each 25 revolution of the type-carrying cylinder with an inking-roller. The latter construction is here shown, the inking-roller G (Figs. 1 and 2) being mounted above the type-carrying 30 cylinder C. The ends g of the shaft of this roller are received in notches at the top of the side-frames B, B', and are held in these notches by pins g' .

Extending between the heads c', c^2 , of the 35 type-carrying cylinder C, is a bar I, one end of which is received in an opening in the head c' and the other end of which enters a slot in the head c^2 , where it is held by a screw i (Fig. 3). The bar I is cut away along one edge, 40 as shown at i' in Figs. 1 and 3, to receive a rod i^2 and projections i^3 are formed upon the bar to hold rod i^2 in the position in which it is shown in Figs. 1, 2 and 3, between projections i^3 and the surface of the cut-away portion of bar I.

The transfer fabric J has one end secured 45 to the rod i^2 and extends from the rod around a substantial portion of the type-carrying cylinder C, and its other end is secured to a rod k . This rod is held in position by a plurality of prongs k' carried by a shaft K, which is mounted for rotation in bearings formed in the heads c', c^2 . One end of rod k extends through the head c' and carries a ratchet 50 wheel k^2 (Fig. 6), with which coacts a pawl k^3 pivotally mounted upon head c' . Thus, by rotating the shaft K, the transfer fabric may be drawn taut and the shaft K will be held in this position by the pawl k^3 and 55 ratchet k^2 .

Each line of type is carried by a disk-like type-holder, and the several holders are mounted upon the type-carrying cylinder by removing one of the heads c', c^2 from the shaft c , inserting the type-holders upon the 70 shaft and then replacing the head. The construction of the type-holders is shown in detail in Figs. 7 to 10. Each holder consists of two plates L and M, which are preferably of sheet-metal pressed to the desired form. 75 The plate L throughout a substantial portion of its circumference is of greater radius than throughout the remaining portion, and at its outer edge has an upwardly turned flange l having the radially-extending parts l^2 and l^4 . At the center of the plate, an upwardly extending hub l' is formed, and at the upper end of this hub are a plurality of radially disposed projections l^2 . The plate M has a portion of greater radius than the remaining 80 portion, to correspond with the plate L, but the portion of greater radius does not extend out to the edge of the corresponding portion of the plate L. A plurality of notches m^2 are cut in the plate M about the central 85 opening therein, to correspond with the projections l^2 upon the plate L. Each type N has a notch cut in one side thereof to receive the flange l , and through about half its length at the end opposite the type-face it is reduced in size. In assembling the type, the 90 plate L is held in one hand and the type are placed thereon successively, each type being radially disposed with the flange l entering the notch n therein and the first type being placed against the wall l^2 at the end of the portion of the plate which is of the greater radius. After a number of type have been 95 assembled, the plate M is placed in position upon the assembled type and the plate L and is turned until the notches m^2 therein align with the projections l^2 on the plate L, as shown in Fig. 7. Plate M is then depressed until it lies below the projections l^2 and then turned so that it is held upon the plate L by 100 the projections l^2 , as shown in Fig. 8. When in this position, the edge of plate M overlies the portions of the type which are reduced in size. The assembling of the type can then be continued and after a substantial number 105 of type have been placed in position the plate M may be turned around upon the hub of the plate L to hold the type which have been assembled against displacement. The entire space between the walls l^2 and l^4 is thus filled with type or quads, and the plate M is turned on the hub l' until the portion of the plate which is of greater radius overlies the inner ends of all of the type, so that the latter are held against lateral movement by 110 plate M and against movement radially outward by the flange l .

When type have been assembled in a sufficient number of the holders for printing the desired matter, these holders are assembled 115

upon the type-carrying cylinder. For this purpose one or both of the ends of the transfer fabric are removed from the type-carrying cylinder, this being done by turning the 5 pawl k^3 on its pivot so as to allow the shaft K to turn until the prongs k' release the rod k . The cylinder is removed from the machine 10 in the manner above explained, and the head c^2 of the cylinder withdrawn from the end of shaft c , the screw i being first removed to permit this. The type-holders are then inserted upon shaft c with the type lying between the rod I and the shaft K ; the head c^2 is then replaced upon the end of shaft c and 15 the cylinder again mounted in position upon the side-frames of the machine. The transfer fabric may then be again mounted in position by carrying the rod k over the prongs k' and turning shaft K until the fabric is 20 drawn taut.

The operation of the machine will be readily understood from the foregoing description. The impression-sheets are placed upon the feed-board F and fed forwardly 25 successively to the line of coaction of the feed-rollers f, f' . The cylinder is rotated by operating the handle E and in each revolution of the cylinder the feed-rollers are actuated to feed a sheet over the platen-roller D just 30 before the forward ends of the several lines of type come around into position to coact with the platen-roller through the impression-sheet and transfer fabric. As the rotation of the cylinder continues, the sheet is fed 35 forward and imprinted upon the type.

It will be seen that the simplicity of the construction and the facility with which it may be operated make it particularly well adapted for use in offices where it would be 40 run by an unskilled operator for printing duplicate copies of letters and circulars. By reason of the delicate adjustment of the platen-roller with respect to its distance from and parallelism to the type-cylinder and also 45 the arrangement of the type in lines extending in the direction of the printing movement, clear and evenly printed impressions may be obtained. By using suitable type, 50 impressions in close imitation of typewritten matter may be made.

The construction of the type-holders and the method of mounting them upon the cylinder is simple and convenient, so that an unskilled operator quickly acquires facility 55 in assembling the type for printing.

Having now described my invention, what I claim as new therein and desire to secure by Letters Patent is as follows:—

1. In a printing machine, the combination 60 of a frame, a type-cylinder mounted for rotation thereon, a plurality of type-holders mounted on the cylinder, a line of individually assembled type supported by each of said holders and extending circumferentially 65 of the cylinder, the several holders, each with

its line of type, being removable from the cylinder, an inking device, means for rotating the cylinder, and a platen movable in correspondence with the movement of the type-cylinder, substantially as set forth. 70

2. In a printing machine, the combination of a frame, a type-cylinder mounted for rotation thereon, a plurality of type-holders mounted on the cylinder, a line of individually assembled type supported by each of 75 said holders and extending circumferentially of the cylinder, the several holders, each with its line of type, being removable from the cylinder, an inking-ribbon overlying the printing faces of the type and removably 80 mounted on the cylinder, means for rotating the cylinder, and a platen movable in correspondence with the movement of the type-cylinder, substantially as set forth. 85

3. In a printing machine, the combination of a frame, a type-cylinder mounted for rotation thereon, a plurality of type-holders mounted on the cylinder, a line of individually assembled type supported by each of said 90 holders and extending circumferentially of the cylinder, the several holders, each with its line of type, being removable from the cylinder, an inking device, means for rotating the cylinder, a rotatable platen-roller adjacent to the cylinder, and means for moving 95 the platen-roller toward and away from the cylinder, substantially as set forth.

4. In a printing machine, the combination of a frame, a type-cylinder mounted for rotation thereon, a plurality of type-holders 100 mounted on the cylinder, a line of individually assembled type supported by each of said holders and extending circumferentially of the cylinder, the several holders, each with its line of type, being removable from the cylinder, said lines of type extending around but a portion of the cylinder, a transfer fabric overlying the printing faces of the type, means for supporting the ends of the fabric upon the cylinder beyond the ends of said 105 lines of type and within the circle of the printing faces of the type, and a platen movable in correspondence with the rotation of the type-cylinder, substantially as set forth. 110

5. In a printing machine, the combination of a frame, a shaft mounted for rotation thereon, a plurality of annular type-holders on said shaft, a line of individually assembled type supported by each of said holders and extending circumferentially of the shaft, 115 the several holders, each with its line of type, being removable from the shaft, an inking device, and a platen movable in correspondence with the movement of the type, substantially as set forth. 120

6. In a printing machine, the combination of a frame, a shaft removably mounted thereon, a plurality of annular type-holders through which said shaft extends, a line of individually assembled type supported by each 130

- of said holders and extending circumferentially of the shaft, the several holders, each with its line of type, being removable from the shaft, an ink-ribbon overlying the printing faces of the type, means for rotating said shaft and the type-holders thereon, and a platen-roller coacting with the printing faces of the type, substantially as set forth.
7. In a printing machine, the combination of a frame, a shaft removably mounted thereon, a plurality of annular type-holders through which said shaft extends each adapted to support a line of type extending circumferentially of the shaft and the several holders, each with its line of type, being removable from the shaft, an ink-ribbon mounted on the shaft and overlying the printing faces of the type, said ribbon being removable from the shaft, means for rotating said shaft and the type-holders thereon, and a platen coacting with the type, substantially as set forth.
8. In a printing machine, the combination of a frame, a shaft removably mounted thereon, a plurality of annular type-holders through which said shaft extends each adapted to support a line of type extending circumferentially of the shaft and the several holders, each with its line of type, being removable from the shaft, a transfer fabric overlying the printing faces of the type, means for supporting the ends of the fabric upon said shaft beyond the ends of the lines of type and within the circle of the printing faces thereof, means for rotating said shaft and the type-holders thereon, and a platen movable in correspondence with the rotation of the type, substantially as set forth.
9. In a printing-machine, the combination of a type-cylinder, means for supporting type thereon, an inking device, a rotatable platen-roller in co-operative relation to the type-cylinder, a shaft adjacent to the roller, means for rotating the same, means for locking the shaft in position, cams on said shaft, screws carried by the platen-roller near its ends and adjustable relatively to the roller in threaded openings, said screws having their ends bearing on said cams, and means for locking the screws in position, substantially as set forth.
10. In a printing-machine, the combination of a type-cylinder, type supported thereon, a transfer fabric overlying the printing faces of the type, means for securing one end of the fabric to the cylinder, a rod to which the other end of the fabric is secured, a shaft mounted in bearings on the cylinder, prongs on said shaft adapted to coact with said rod and means for locking the shaft against rotation, substantially as set forth.
11. In a printing-machine, the combination of side-frames, a type-cylinder journaled therein and removable therefrom, said cylinder consisting of a shaft and heads mounted thereon and one of said heads being removable from the shaft, type-holders on said shaft between said heads each adapted to support a line of type extending circumferentially of the cylinder and the several holders, each with its line of type, being removable from the cylinder, a transfer fabric mounted upon the cylinder overlying the printing faces of the type thereon, means for rotating the cylinder and a platen movable in correspondence with the movement of the cylinder, substantially as set forth.
12. In a printing-machine, the combination of a cylinder consisting of a shaft and heads mounted thereon, one of said heads being removable from the shaft, type carried by the cylinder, side-frames, pins extending through openings in the frames and engaging the ends of the shaft of the cylinder, one of said pins being movable axially to disengage said shaft, means for rotating the cylinder, an inking device, and a platen movable in correspondence with the movement of the cylinder, substantially as set forth.
13. In a printing machine, the combination of a cylinder consisting of a shaft, heads thereon, two bars extending between said heads, a plurality of annular type-holders on said shaft between said heads each adapted to support a line of type extending circumferentially of the cylinder and the several holders, each with its line of type, being removable from the cylinder, said type-holders being held against movement circumferentially of the cylinder by said bars, an inking device, means for rotating the cylinder, and a platen movable in correspondence with the rotation of the cylinder, substantially as set forth.
14. In a printing machine, the combination of a cylinder consisting of a shaft, heads thereon, two bars extending between said heads, a plurality of annular type-holders on said shaft between said heads each adapted to support a line of type extending circumferentially of the cylinder and the several holders, each with its line of type, being removable from the cylinder, said type-holders being held against movement circumferentially of the cylinder by said bars, an ink-ribbon overlying the printing faces of the type, means on said cylinder between said bars for carrying the ends of the ribbon, means for rotating the cylinder and the type thereon, and a rotatable platen-roller coacting with the printing faces of the type, substantially as set forth.
15. In a printing-machine, the combination of side-frames, a cylinder journaled therein and removable therefrom, said cylinder consisting of a shaft and heads thereon one of which is removable from the shaft, a plurality of annular type-holders on said shaft, means for preventing rotation of the holders on the shaft, a line of type carried by each holder and extending about a portion of

- the periphery of each holder, a transfer fabric overlying the printing faces of the type, supports for the ends of the fabric carried by the cylinder one on each side of a page-form 5 of type in said holders, one end of said fabric being removable from the cylinder, means for rotating the cylinder, and a platen movable in accordance with the movement of said cylinder, substantially as set forth.
- 10 16. In a printing-machine, a type-carrying member and a plurality of type-holders thereon each consisting of two annular plates, a portion of each plate being formed on an arc of greater radius than another portion 15 thereof, and means operated by a rotational movement of one plate relatively to the other for securing the plates together to hold a line of type between them with the printing faces of the type projecting beyond the edges of 20 the plates, substantially as set forth.
17. In a printing-machine, a type-carrying member and a plurality of type-holders thereon each consisting of two plates having integral radial projections thereon spaced 25 apart and adapted to secure the plates together to hold a line of type between them with the printing faces of the type projecting beyond the edges of the plates, substantially as set forth.
- 30 18. In a printing-machine, a type-carrying member and a plurality of type-holders thereon each consisting of two annular plates one having a hub and projections on the hub and the other having notches corresponding 35 to said projections for securing said plates together to hold a line of type between them with the printing faces of the type projecting beyond the edges of the plates, substantially as set forth.
- 40 19. In a printing-machine, a type-carrying member and a plurality of type-holders thereon each consisting of two plates each having a substantial portion of its periphery formed on the arc of a circle and one having a flange about the edge of said circular portion and means for securing said plates together to hold a line of type between them with said flange entering a notch in each type and the end type of the line lying against the flange at the end of said circular portion, substantially as set forth. 45
20. In a printing-machine, the combination of a type-carrying member, a plurality of type-holders thereon each consisting of two plates, the edge of one extending beyond the edge of the other and being provided with a flange at said edge, and type each cut away on one side at one end and having a notch in the other side, said flange on one of the plates entering said notches in the type and the edge of the other plate overlying said cut-away portions, substantially as set forth. 50
21. In a printing-machine, a type-holder consisting of two annular plates and means for securing them together, the edge of one 55 of the plates extending beyond the edge of the other and being provided with a flange at said edge, and type each cut away on one side at one end and having a notch in the other side, said flange on one of the plates 60 entering said notches in the type and the edge of the other plate overlying said cut-away portions, substantially as set forth. 65
- This specification signed and witnessed this 14th day of October, 1907.
